UNITED STATES PATENT OFFICE.

LEVI F. SMITH, OF PHILADELPHIA, PENNSYLVANIA.

DESIGN FOR OIL-RESERVOIRS FOR LUBRICATORS.

Specification forming part of Design No. 7,785, dated September 29, 1874; application filed September 12, 1874.
[Term of Patent 14 years.]

To all whom it may concern:

Be it known that I, LEVI F. SMITH, of Philadelphia, in the county of Philadelphia and in the State of Pennsylvania, have invented certain new and useful Improvements in Design for Oil-Reservoir for Lubricators; and do hereby declare that the following is a full, clear, and exact description thereof, reference being had to the accompanying drawings, and to the letters of reference marked thereon, making a part of this specification.

My design is fully represented in the accompanying drawings.

B represents a vessel, having at the top and bottom suitable bands A A', for the connections to be attached. The vessel is usually formed of one piece of metal, and is composed of a series of bands separated by beads. Below the connecting band A, and above the band A', is a narrow concave fillet, Z Z'. Extending downward from the fillet Z, and upward from the fillet Z', is an outwardly-curved band or section, α and α' . Below the band α , and above the band α' , is a bead, X and X', from which extend each way a plain band, b and b' . At the inner ends of these bands is a fillet, S and S'. Between these last two fillets the vessel is enlarged at the center by the two outwardly-curved bands C C', the center of which is encircled by a flat band, y , with concaved edges, as shown.

This construction of oil-reservoir gives it a neat and marked appearance, and is applicable to any construction of oil-lubricator wherein an oil-reservoir is required.

What I claim is—

The design for oil lubricating - vessel, as shown and described.

In testimony that I claim the foregoing I have hereunto set my hand this 8th day of September, 1874.

LEVI F. SMITH.
